UNITED STATES PATENT OFFICE.

GEORGE S. GOODWIN, OF CHICAGO, ILLINOIS, ASSIGNOR TO WALTER Murphy
CHICAGO, ILLINOIS.

END REINFORCEMENT FOR BOX-CARS.

1,282,568.

Specification of Letters Patent.

Patented Oct. 22, 1918.

Application filed March 24, 1916. Serial No. 86,402.

To all whom it may concern:

Be it known that I, GEORGE S. GOODWIN, a citizen of the United States, residing at Chicago, in the county of Cook and State 5 of Illinois, have invented certain new and useful Improvements in End Reinforcements for Box-Cars, of which the following is a specification.

My invention relates to railway box cars, 10 more particularly cars of wood construction, and one of the principal objects of the invention is to provide certain reinforcing means for strengthening the car against cargo thrusts and other shocks and impacts 15 from within and from without to which the end wall of a railway car is liable when the car is in service.

A further object of the invention is to rigidify the end framing of the car as 20 against weaving and other like stresses which tend to racking and ultimately destroy the superstructure and roof of a box car.

A further object is to provide an end reinforcement for a box car of wood construction 25 which can be readily applied in repairing old cars as well as in the construction of new cars.

A further object is to provide reinforcing means of the general character above described which will give a maximum of 30 strength and rigidity with a minimum increase of weight.

A further object is to arrange vertical, or 35 substantially vertical, reinforcing members on the outside of the car which will be so disposed as not to violate the provision of the Interstate Commerce Commission with reference to end ladder clearance; the placing of such members on the outside of the car 40 having the advantage that the effective inside length of a car is not thereby diminished.

With the above stated objects in view, 45 my invention consists in the arrangements, constructions and devices to be hereinafter described and claimed.

The invention is illustrated, in a preferred embodiment, in the accompanying drawings, wherein—

50 Figure 1 is an end elevation of the superstructure of a railway box car of standard wood construction.

Fig. 2 is a top plan view of the end of the car showing the roof boards removed.

and certain parts of the framing and sheathing in section.

Fig. 3 is a vertical sectional view on line 3—3 of Fig. 1.

Fig. 4 is a view, in perspective, of the inner bracing member forming, preferably, a 60 part of the reinforcing structure of my invention.

Fig. 5 is a view, in elevation, showing a modified construction, and

Figs. 6 and 7 are sectional views on lines 65 6—6 and 7—7, respectively, of Fig. 5.

Like characters of reference indicate like parts in the several figures of the drawings.

In the drawings, 10 indicates the end sill at one end of the car, 11 the end plate, 12, 12 70 the corner posts, 13, 13 the usual end posts intermediate the corner posts, 14, 14 the side plates, 15 the outer end sheathing, and 16 the inner end sheathing or lining, the sheathings, in the construction shown, being both 75 of wood, although that is not essential.

In order to strengthen the end wall and rigidify the end of the superstructure of the car as a whole, vertical or substantially vertical reinforcing members 17 are arranged on the outside of the car parallel with the end posts 13 and bolted thereto by bolts 18, these bolts serving also to secure the inner lining 16 in place against the end posts 13 and the usual end girths 19 of the 80 end framing. I have shown a car of standard wood construction. It will be obvious, however, that the reinforcing structure of my invention might be used in connection with cars not constructed precisely as shown. 90

These reinforcing members are angular in cross-section. Preferably they are Z-bars. Although they project out from the sheathing of a car, they stand close enough to the vertical center line of the end that they do 95 not violate the regulation of the Interstate Commerce Commission with reference to end ladder clearance. Therefore, being on the outside, the reinforcement, as described, does not necessitate any shortening of the 100 car body.

The lower ends of the reinforcing members 17 are preferably anchored to the framing of the car by means of the truss rods 20 which extend through the under frame 105 ordinarily from end to end of the car. The upper extremities of the reinforcing members are secured to the end plate 11 by bolts

21. These same bolts may be employed for attaching to the end plate of the car a horizontally arched steel reinforcement 22 preferably consisting of a single rolled steel element angular in cross section, the middle portion 23 of which lies flatwise against the end plate and the extremities or corner brace members 24 of which are bent so as to extend diagonally across the corners of the 10 car to the side plates 14 of the car to which they are attached by bolts 25. The structure is preferably further rigidified and strengthened by truss rods 25^a which extend across the upper part of the car from 15 one side plate to the other. The vertical reinforcing members 17, the horizontally disposed arched brace 22, structurally united to the upper ends of the reinforcing members, and the truss rods 20 which anchor the lower 20 ends of the reinforcing members of the car framing together constitute a reinforcing structure of a unitary character which, besides giving the end of the car greater capacity for 25 resisting cargo thrusts and like shocks and impacts, serves also to greatly stiffen and rigidify the end of the car superstructure as a whole more particularly against the racking or weaving strains to which railway box cars are subject because of the various swinging 30 or swaying movements of the cars, for example, in rounding curves or resulting from the inequalities of the track. The extremities of the reinforcing member 22 are attached to the side plates 14 close to one of 35 the roof carlines 14^a, which latter forms a strut or compression member between the side plates, preventing the side plates from being drawn in by the reinforcing member 22 when the cargo exerts an outward thrust 40 against the end of the car. This reinforcing structure may be readily applied to old cars as well as new ones. If any of the parts are injured, they may be easily replaced without disturbing the other parts of 45 the car structure.

In some cars the truss rods are not in line with the end posts. For example, it happens not infrequently that the truss rods are nearer the sides of the car than the end posts. 50 To meet this contingency my invention may be modified as indicated in Figs. 5 to 7, inclusive. In the car shown in these figures the truss rods 26 are nearer the sides of the car than the end posts 27. The reinforcing 55 members 28 are anchored to the car at their lower ends by the truss rods 26. However, instead of being vertical they slant somewhat toward each other so that they cross the end posts 27 as shown. The upper ends 60 of the reinforcing members may be anchored to the car by means of an arched brace 29 of the same sort as the brace 22 shown in the construction shown in Figs. 1 to 3 inclusive. The reinforcing members are preferably bolted or otherwise secured to the girth 65

members 30 of the end posts 27 and to the diagonal braces 31. In order to prevent the lower ends of the end posts from being kicked out by a cargo thrust against the lower part of the end I provide a casting 70 32 which also serves as a buffer casting. This casting is bolted to the end sill 33 and bears against the flanges 34 of reinforcing members 28. The truss rods 26 extend through the casting as well as to the reinforcing members 28 and end sill. 75

I do not claim herein specifically the construction shown in Figs. 5 to 7, inclusive, as this structure is disclosed and claimed in a copending application filed March 27, 1918, Serial No. 224,951.

While I have described my invention in certain preferred embodiments, further modifications might be made without departure from the principles of the invention. 85 Therefore I do not wish to be understood as limiting the invention to the precise constructions, devices and arrangements shown except as the claims may be so limited.

I claim:

1. In a railway car, the combination with the framing of the car comprising side plates and end posts, of metal reinforcing members on the outside of the end wall of the car secured to said end posts, and a metal bracing structure within the car secured to said reinforcing members and comprising diagonally extending members attached to the side plates at points remote from the corners of the car. 90

2. In a railway car, the combination with the framing of the car comprising side plates and end posts, of metal reinforcing members on the outside of the end wall of the car secured to said end posts, and an integral metal brace secured to said reinforcing members at points near the middle of said brace, with its extremities bent so as to extend diagonally to the side plates of the car and anchored at the ends to said side plates. 105

3. In a railway car, the combination with the framing of the car comprising side plates and end posts, of metal reinforcing members on the outside of the end wall of the car secured to said end posts, a metal bracing structure secured to said reinforcing members and comprising members extending diagonally from the end posts to the side plates of the car and anchored at their extremities to said side plates, and truss rods anchoring the lower ends of said reinforcing members to the underframe of the car which extend longitudinally of the under frame. 115

4. In a railway car, the combination with the framing of the car comprising side plates and end posts, of metal reinforcing members on the outside of the end wall of the car secured to said end posts, a metal bracing structure secured to said reinforcing mem- 120

130

- bers and comprising members extending diagonally from the end posts to the side plates of the car and anchored at their extremities to said side plates, and a transverse 5 truss rod extending from side plate to side plate adjacent the ends of said brace.
5. In a railway car, the combination with the framing of the car comprising side plates and end posts, of metal reinforcing members 10 angular in cross section on the outside of the end wall of the car secured to said end posts, and a metal bracing structure angular in cross section secured to said reinforcing members at points near the middle of said 15 brace, with its extremities extending and attached to the side plates.
6. In a railway car, the combination with the framing of the car comprising side plates and end posts, of metal reinforcing members 20 angular in cross section on the outside of the end wall of the car secured to said end posts, and an integral metal brace angular in cross section secured to said reinforcing members at points near the middle of said brace, with 25 its extremities bent so as to extend diagonally to the side plates of the car and anchored to said side plates.
7. In a railway car, the combination with the framing of the car comprising side plates and end posts, of metal reinforcing members 30 on the outside of the end wall of the car secured to said end posts, a metal brace secured to said reinforcing members at points near the middle of said brace, with its extremities extending and attached to the side plates, and truss rods extending longitudinally of 35 the car which anchor the lower ends of said reinforcing members to the under frame of the car.
40. 8. In a railway car, the combination with the framing of the car comprising side plates and an end plate, of a metal bracing structure, the middle portion of which lies against the end plate and is anchored thereto, said structure being provided with angularly disposed portions which extend from the end plate to the side plates and are secured at their extremities to said side plates.
9. A reinforcing structure for the end wall 50 of a box car, comprising a pair of substantially upright end reinforcing members on the outside of the wall of the car, and a substantially horizontal arched bracing structure within the car attached at the middle to the reinforcing members and at its extremities to the opposite sides of the car framing at points remote from the corners of the car.
10. A reinforcing structure for the end wall 55 of a box car, comprising a pair of substantially upright end reinforcing members on the outside of the wall of the car, a substantially horizontal arched bracing structure within the car attached at the middle to the upright reinforcing members and at its extremities to the opposite sides of the 60
- car framing at points remote from the corners of the car, and truss rods for anchoring the lower ends of said reinforcing members to the under frame of the car.
11. In a railway car, the combination with 70 the framing and end wall of the car, comprising substantially vertical end posts, of reinforcing members consisting of Z-bars arranged on the outside of the car wall secured to said end posts, truss rods which 75 anchor the lower ends of the reinforcing members to the under frame of the car, and a horizontal arched brace secured to the upper ends of the reinforcing members and to the side members of the car framing. 80
12. In a railway car, the combination with the end and side walls of the car, of a metal reinforcement for the same comprising a pair of substantially upright beams on the outside of the end wall, means for securing 85 the lower ends of said beams to the under frame of the car and a metal bracing structure within the car comprising diagonally disposed members for securing the upper ends of said beams to the side walls. 90
13. The combination with the side plates and end wall of a railway box car, of a reinforcing and bracing member, the middle portion of which lies parallel to and is secured to the upper portion of the end wall 95 of the car, the ends of which extend diagonally across the car and are attached to the side plates.
14. The combination with the end wall sheathing, end plate and side plates of a railway box car, of reinforcing means for the end plate comprising diagonal brace members extending across the corners of the car and rigidly anchored to the end plate near the middle thereof and side plates at points 100 remote from the corners of the car. 105
15. The combination with the end wall and side walls of a railway box car, of substantially upright reinforcing members for the end wall and a bracing structure comprising members extending across the corners of the car and rigidly anchored to the middle portion of the end wall and to the side walls of the car at points remote from the corners of the car. 110
16. The combination with the side plates and end wall of a railway box car, of a reinforcing structure which is attached to the upper part of the end wall with its extremities anchored to the side plates at points remote from said end wall, and a carline interposed between the side plates at points adjacent the extremities of said reinforcing structure so as to act as a compression member as against the tendency of the side plates 115 to be drawn together when an outward stress is exerted against the inside of the end wall. 120
17. In combination in a car having side and end plates, a rigid frame spanning from side plate to side plate and comprising diag. 130

onal members connecting the side plates to the end plate, said members being rigidly secured to the end plate and having their ends secured to the side plates.

18. In a car end construction, in combination with side plates, end plate, end sill and end posts, a pair of end braces, each of which is secured to said end plate, sill and post, and a rigid frame secured to said end 10 braces and to said side plates and end plate for maintaining them in rectangular alignment.

19. In combination with the end and side

walls of a railway box car, of substantially upright metal reinforcing members on the 15 outside of said end walls, means for anchoring the lower ends of said members to the under frame of the car, and reinforcing means within the car comprising members extending diagonally across the corners of 20 the car rigidly connecting the upper ends of said upright reinforcing members to the side walls of the car at points remote from the corners of the car.

GEORGE S. GOODWIN.
